UNITED STATES PATENT OFFICE.

ALBERT H. BUCKELEW, OF NEWARK, NEW JERSEY.

MOTOR-CONTROLLER.

No. 905,790.

Specification of Letters Patent.

Patented Dec. 1, 1908.

Application filed February 21, 1905. Serial No. 246,727.

To all whom it may concern:

Be it known that I, ALBERT H. BUCKELEW, a citizen of the United States, residing at Newark, in the county of Essex and State of New Jersey, have invented certain new and useful Improvements in Motor-Controllers, of which the following is a full, clear, and exact specification.

This invention relates to motor controllers and more particularly has reference to that class of devices in which the controller is operated by a pilot motor, the latter being controlled by manual switches.

The object of the invention is to provide a mechanism of this character by which the operator can control the main motor at various speeds from directional switches alone, without necessitating his attention to the positions of the controller for different speeds.

The invention is particularly applicable to the control of one or more motors which it is desirable to run at various speeds in both directions.

As usually constructed, dental or surgical engine motors, in particular, are controlled by a small controller which is moved by the foot of the operator for different speeds and directions. This necessary positioning of the controller distracts the attention of the operator from the work in hand, causing delay and possible injury to the patient. By this invention, I provide a pilot motor to move the main controller step by step in either direction, through push buttons or other switches, which require no more attention from the operator than the force necessary to actuate them.

The invention will be more fully described with reference to the form thereof shown in the accompanying drawings, in which—

Figure 1 is a top plan view, the cover being removed, Fig. 2 is a vertical section, Fig. 3 is a detail view at right angles to Fig. 2, seen from the left. Figs. 4 and 5 are detail views of the intermediate devices for stopping the pilot motor automatically, Figs. 6 and 7 show the center stop. Figs. 8, 9, 10, 11 and 12 represent forms of contact devices. Fig. 13 is a diagram showing the electrical circuits.

Referring to Figs. 1 and 2, 1 represents a base carrying a side casing 2 and a removable cover 3. Pivotaly mounted on the lugs 4, so as to swing vertically relatively to the base is a framework 5, carrying the pilot motor. The pilot motor comprises an arma-

ture 7, field magnets 8, armature shaft 9, brushes 10, commutator 11. The armature shaft 9 has a worm which meshes with a gear 13 carried by a shaft 14 journaled in the frame 5. On the end of shaft 14 is a gear 15 which meshes with a segmental gear 16 carried by a revoluble spider 17 journaled in the casing 1. Mounted to turn with the gear 16 is the controller arm 18 which moves over contacts within the case 19 for controlling the main motor, a certain position of the arm 18 at either side of the center, corresponding to a certain speed of the main motor in one or the other direction.

The operation of the device generally, so far as described is as follows: The pilot motor always runs at the same speed and by reversing the fields in a manner to be hereafter described, is made to run in either direction at the will of the operator. The pilot motor having been started, it will be seen that the speed and direction of the main motor will depend upon the position of the controller arm which is governed by the movement of the gear 16 derived from the pilot motor. I have provided means whereby a single actuation of the operator's switch will start the pilot motor and move the controller arm to such position as to set the main motor in operation at its first speed. When this position is reached the pilot motor is automatically stopped. In case it is desired to run the main motor at its second or any other speed, a further actuation of the operator's switch will again start the pilot motor and move the main controller to the next position. If it is desired to reverse the main motor, means is provided by which this can be done through a step-by-step movement of the controller, or a quick movement, as may be desired. It is thus possible to go back to the center from any of the different speeds, step-by-step, through the operator's switch; and it is also possible to cause a quick stop by bringing the controller back to center without this step-by-step movement. This latter result is accomplished by swinging the pilot motor frame carrying the pinion 15, out of engagement with the gear 16, leaving the controller gear 16 free to be swung back to center by any suitable centering device, such as the two armed spring 40 (see Fig. 2). This spring 40 is coiled around the shaft of the main controller arm 18, and its two arms bear on opposite sides of a movable pin 41, carried on arm 18, and a fixed pin 42 mount-

ed on the lower side of the main controller 19. It will be seen that the pin 41 is free to move in either direction against one or the other arm of the spring and that when the gear is released the spring acting on the pin 41 will return the controller arm 18 to central position and also the gear 16. In order to tilt the pilot motor frame and disengage the gear 15 from the gear 16, for a quick stop of the main motor, I have provided a pair of magnets 42 and 43 which are carried on the base 1. These magnets are of the "iron clad" type, and to the casing of each is pivoted an armature 44. Connected with each armature 44 is a small cable 45 which passes over a pulley 46 carried by the pilot motor frame. The magnets 42 and 43 are in the pilot motor circuit and are controlled by the operator's hand switch, and when both magnets are simultaneously energized the armatures 44 will be pulled down together, carrying the pilot motor frame with them, against spring 71, disengaging the gear 15 from the gear 16, thus leaving the controller arm 18 free to be turned to the central position by spring 40. In returning step-by-step to central position, the one or the other of the magnets 42, 43 is energized, according to the direction of the pilot motor, and as soon as one armature 44 is pulled down the other will correspondingly rise, producing no movement of the pilot motor frame.

49 is a brake magnet in the pilot motor circuit which actuates a brake lever 50, pivoted at 51, controlled by a spring 52 and carrying a brake shoe 53. Whenever the magnet 49 is deenergized by stopping the pilot motor the spring 52 causes the brake to be applied in a well known manner. As the brake shoe 40 is held out of engagement only when the fields of the motor are energized, it will be obvious that I can, by properly disposing the armature, utilize the magnetism of the fields themselves for actuating the brake, instead of providing a separate magnet.

Figs. 8, 9, 10, 11 and 12 show contact devices which are particularly adapted for dentists' use. Figs. 8, 9 and 10 show a form of finger ring 55, carrying two push buttons 56, 57 and connected by a three wire cable 58 to the pilot motor. Figs. 11 and 12 show a clamp adapted to be attached to the shoe of the operator, comprising a spring bow 59 having clamps 60 and bent upwardly as at 61 at the toe portion. Mounted in the underside are the push buttons 56 and 57 which can be operated singly or simultaneously by pressure against the floor.

The electrical connections are shown in Fig. 13 and are as follows: 62 is a battery or other suitable source of current supply which is connected by a wire 63 with the push buttons 56 and 57. Wire 64 leads from the push button 56, through magnet 42, wire 65, field magnets 8, wire 66, brushes 10 through ar-

mature 7 of the pilot motor and thence by wire 67 through brake magnet 49 and wire 68 to the battery. By closing the circuit through the button 56 it will therefore be seen that the pilot motor will be started and rotated in one direction. For the sake of convenience, it will be assumed that the push button 56 will cause the gear 16 to travel clockwise, in Fig. 1, and the push button 57 to revolve the gear in the opposite direction. The pilot motor having been started, will continue in operation until the gear 16 has revolved latch 36 over high portion 34 of the roller, which causes a circuit to be closed through contacts 38 and 39 (see Fig. 4). As soon as the current passes through the fields 8 of the motor the lever 30 will be attracted by the field magnet so as to bring the roller into the path of the latch 36. Contacts 38 and 39 are in a shunt circuit around the pilot motor armature and the brake magnet 49 so that whenever the contacts 38 and 39 are closed the armature will be short circuited upon itself forming a dynamic brake, and the brake magnet shunted, permitting the spring 52 to apply the mechanical brake, thus stopping the pilot motor at this point. Upon releasing the push button 56 the motor field magnet is deenergized and spring 32 withdraws the roller from under latch 36, thus opening contacts 38 and 39. See Fig. 5. The main motor controller has now been moved to a position for its first speed, and is held against spring 40 in this position by the brake. If now it is desired to run the main motor at its next speed, the push button 56 is again operated to move the gear 16 further and thereby the main controller, another step to secure this next speed by the same sequence of operations. It will be observed that if by inadvertence the operator does not release the push button 56 after he has caused the main controller to be moved to the desired position, no harm results because the pilot motor is positively stopped by the closing of contacts 38 and 39, thus preventing an accidental movement to a higher speed than desired. After having been once closed to stop the motor, the contacts 38, 39 hold it stopped as long as they remain closed, that is to say, until the spring 32 withdraws the roller from under latch 36. This cannot occur until the magnet controlling the lever 30 is deenergized, which, if the field magnet be used or a magnet in circuit therewith, occurs when the operator releases the push button, thereby releasing the lever 30 and opening the contacts 38, 39. After the lever has moved outward, the motor can again be started in either direction by the push button.

In order to bring the main motor step-by-step to center the operator will actuate the push button 57, which will cause the pilot motor to operate in the opposite direction through wire 70 magnet 43, fields 8, wire 66, 130

brush 10, armature 7, wire 67, brake magnet 49, wire 68, as before. As soon as lug 26 of the central latch 25 has struck the lower portion 35 of the roller, the contacts 38 and 39 will be again closed (Fig. 6), thus stopping the pilot motor at the central position.

It will be seen that in order to again start the pilot motor, the contacts 38 and 39 must be opened, and this can only be done at the center position by tilting the pilot motor frame by pressing both push buttons 56 and 57 at once, to energize both magnets 42 and 43. When both push buttons are operated simultaneously, which can be done from any position, the fields of the pilot motor being opposed to each other, become neutral, so that as soon as the frame drops sufficiently, the spring 32 will throw the roller outward opening contacts 38 and 39 Figs. 7 and 13. This can be done from any position as the roller in its lower outward position (Fig. 7) clears all the latches 36.

Fig. 5 shows the position after a push button has been released at one of the stops so that another actuation of the push button will move the main controller to the next speed. It will also be seen that in returning to center step-by-step, as in Fig. 6, the pilot motor cannot be started with the main controller in off position until the contacts 38 and 39 are opened or until the high part 34 of the roller can pass under lug 26 of latch 25, which is accomplished by dropping the frame with both push buttons. The spring 71 returns the frame to upper position to reengage the gear 16 with pinion 15 as soon as the push buttons are released, (or one of them) and the roller then lies to the left of the lug 26 in Fig. 7. As soon as the gear has moved sufficiently, the field magnet draws the lever 30, into position to strike the first of the latches 36 to stop the pilot motor. This provision that the motor must always stop at the central position is of considerable importance in dental work because of its delicacy and the necessity of an absolutely reliable control which requires a minimum of attention from the operator and absolute freedom from accidental reversal. By this mechanism just described, all the operator has to do, is to distinguish between his two push buttons and actuate them one or more times to secure any desired forward or backward speed, thus dispensing with the usual foot controlled devices now in use. It will be understood that proper binding posts and wiring arrangements are used to connect up the various circuits. The push buttons may be disposed at any suitable place and the wires may be led to the mechanism through an eyelet 75 in the case.

It is obvious that two or more controllers can be operated simultaneously in multiple by the same mechanism for controlling a plurality of motors simultaneously.

I do not restrict myself to the precise con-

struction herein shown as many modifications and changes may be made without departing from the scope of the invention.

Having thus described my invention, I declare that what I claim as new and desire to secure by Letters Patent, is,—

1. The combination with a motor controller having a plurality of speed regulating positions, of a pilot motor for actuating said controller, a push button for actuating said pilot motor to continuously actuate said controller from one position to another, and means for throwing said pilot motor out of engagement to stop the controller at a determined speed position, substantially as described.

2. The combination with a motor controller having a plurality of speed positions, of push button controlled means comprising a rotating pilot motor for moving said controller to the different positions, and a solenoid controlled by said push button means for disengaging said controller from the pilot motor, whereby said controller may be returned from any running position to off position either step by step or at one actuation of the controlling switch, substantially as described.

3. The combination with a motor controller, of a pilot motor for actuating said controller step-by-step to its running positions without stopping the main motor in going from one position to the next, and means whereby the pilot motor can be disconnected and thrown out of operation and the controller returned to its off position, substantially as described.

4. The combination with a motor controller, of a pilot motor for actuating said controller step-by-step, and a pair of directional switches for controlling the pilot motor without stopping the main motor in going from one position to another, substantially as described.

5. The combination with a motor controller, of a rotary pilot motor for actuating said controller to its running positions without stopping the main motor or controller from going from one position to another, and means whereby the pilot motor can be mechanically disconnected and the controller rotated backward to its off position independently of the motor, substantially as described.

6. The combination with a motor controller, of a pilot motor for actuating said controller to its running positions, said pilot motor having a rotary shaft adapted to engage a rack carried by the controller, means for disengaging the shaft of the pilot motor from the rack and thereby returning the controller to off position, and means for stopping the controller at its off position, substantially as described.

7. The combination with a controller, hav-

ing a pivoted actuating gear, of a rotary pilot motor for engaging said gear to rotate the controller, and means for pivotally rocking one of said parts to disengage the mechanical connection between the pilot motor and the controller and return the controller to off position, substantially as described.

8. The combination with a controller, of a motor for operating the same, independent circuits for operating said motor in either direction, and means whereby the controller is returned to its initial position by closing both circuits, substantially as described.

9. The combination with a controller, a motor for operating the same, independent circuits for operating said motor in either direction, and means for closing both of said circuits and thereby breaking the driving connection between the motor and the controller, substantially as described.

10. The combination with a controller having a plurality of positions, of a motor for operating the same, independent circuits for operating said motor in either direction, and means whereby the reversal of the motor by a single closing of its circuit moves the controller reversely one position, substantially as described.

11. The combination with a motor having circuits for operating it in opposite directions, of a circuit closer for stopping the mo-

tor after a predetermined movement, and means whereby the motor is locked against movement until the circuit closer is opened, substantially as described.

12. The combination with a motor having circuits for operating it in opposite directions, of a circuit closer for stopping the motor after a predetermined movement, means whereby the motor is locked against movement until the circuit closer is opened, and means in the motor circuit for releasing the motor, substantially as described.

13. The combination with a motor and a controlling circuit, of means for automatically stopping and locking the motor after a predetermined movement, and means whereby the motor is released when the controlling circuit is opened, substantially as described.

14. The combination with a motor and controlling circuits, of means for giving the motor a predetermined movement in either direction from its initial position, means for returning the motor to its initial position and automatically locking it, and means for releasing the motor, substantially as described.

In testimony whereof I affix my signature, in presence of two witnesses.
